CLOSURE FRAME MEMBER

Edward R. Gunter, Dubuque, Iowa, assignor to
W. H. Klauer, Dubuque, Iowa

Application May 9, 1938, Serial No. 206,895

4 Claims. (Cl. 189—46)

This invention relates to closure frames and in particular to the provision of a top or head closure frame member incorporating various improvements over prior known constructions.

5 It is an object of this invention to provide such a frame member which is adapted for close association with the top of a door or window aperture and for cooperation with other connected closure frame members for supporting a member 10 such as a window or door.

It is a further object of this invention to provide, in such a top member or section, groove or gutter means offset from a horizontal surface of the member for the collection and drainage 15 of water entering between the top frame member or section and adjacent portions of the building aperture as well as the condensation and collection of moisture between the member or section and the adjacent surfaces.

20 It is a further object of this invention to provide such means which will provide ventilation for the purpose of aiding drying of adjacent building wall portions.

It is a further object of this invention to provide such means whereby additional strength and 25 rigidity of the top frame member or section is secured.

It is a further object of this invention to provide suitably spaced drainage aperture means, 30 in association with the groove or gutter means, for carrying off water or moisture from air space provided by the groove or gutter means between the frame member or section and the adjacent wall surface, while at the same time providing for 35 adequate ventilation of the provided air space.

These and other objects and advantages of the invention will appear from the following description taken in conjunction with the accompanying drawing which forms a part thereof and will 40 be pointed out in the appended claims.

In the drawing:

Fig. 1 is a fragmentary perspective view showing the top or head closure frame member or section of this invention partly broken away in the interest 45 of clearness of disclosure;

Fig. 2 is a fragmentary top plan view of the top section member shown in Fig. 1;

Fig. 3 is a bottom plan view of the structure shown in Fig. 2; and

50 Fig. 4 is a section taken on the line 4—4 of Fig. 2 and illustrating the position of the top frame member with respect to an adjacent portion of a building wall.

Referring to the drawing in detail and with reference particularly to Fig. 1, wherein I have

shown the application of the principles of this invention to the top member or section of a window frame such as that described and claimed in Letters Patent 1,936,513, granted November 21, 1933, to W. H. Klauer, the top member or section 5 is generally designated 1. The top member 1 is adapted for detachable connection to side members 2 in a manner hereinafter more clearly described. The member or section 1 is adapted also for attachment to the portion 4 of the building 10 wall above an aperture as shown in Fig. 4.

The member 1 is provided with a vertical flange portion 5 adapted for association with the outer vertical wall surface adjacent the closure aperture, and extending inwardly from this is a horizontal 15 flange portion 6 adapted for association with the horizontal surface at the top of the aperture. As shown in the drawing, the flange portion 6 is bent back upon itself to form a substantially vertical flange 7 which is, of course, optional. The 20 inner edge of the flange portion 6 is bent back upon itself at 8 to form an inner beaded edge surface. Formed in the flange portion 6 adjacent its forward side, from which extends the vertical flange portion 5, is the groove or gutter 9, having 25 its upper surface disposed below the plane of the upper surface of the flange portion 6 and provided with inclined upper side wall surfaces 10 and like end wall surfaces 11.

Suitable drainage apertures 12 are provided at 30 spaced intervals in the horizontal wall of the groove or gutter 9 for providing ventilation and drainage of moisture collected in the space between the gutter 9 and the adjacent surface of the building wall portion 4.

The flange portion 5 extends outwardly at each end beyond the side edge of the flange portion 6 for the accommodation of integral bent up ears having vertical portions 14 and horizontal portions 15 with slots 16 at the intersection of these 40 horizontal and vertical portions. These slots 16 are adapted to receive end portions or lugs 17 which extend upwardly from the top ends of the side frame members or sections 2.

The portion 17 is co-planar with and integral 45 with the portion 18 of each member 2 and cheeks or side surfaces 19 extend from the portions 18 substantially perpendicularly and terminate in the bent over or beaded portion 20 at the inner inclined edge of each cheek portion 19. The cheek 50 portions 19, as shown in Fig. 1, are provided with flanges 21 formed by bending the cheek portions 19 over upon themselves and these flanges 21, which are optional, are adapted for disposition in the same plane as the flange 7 and have their 55

upper ends inclined in such a manner as to abut closely the end edges of the flange 7.

In assembling the particular embodiment of the invention illustrated, the lug portions 17 are inserted through the slots 16 and may be bent over, if desired, to secure the members 1 and 2 rigidly together, in which case the flanges 21 will form a continuation of the flange 7 which is desirable in window frames such as that illustrated 10 for providing surfaces for close engagement with the glass holding frame of a window structure supported by the closure frame illustrated.

In the illustrated embodiment of the invention, the struck out nature of the groove or gutter 9 materially increases the rigidity of the flange portion 6, while at the same time providing a transverse horizontally disposed air space between a portion of the flange 6 and the adjacent wall surface, and as this air space communicates through apertures 12 to the atmosphere, any water or moisture entering between the member 1 and the wall member 4 will collect in the channel, groove or gutter formed by the member 9 whence it may escape, through the drain aperture 12, to the atmosphere. Likewise, moisture will drain from the wall portion 4 to the groove or gutter and escape in like manner. Due to the provision of inclined side and end walls 10 and 11, the moisture will be directed to the drain apertures 12 to achieve the utmost efficiency of drainage, while at the same time the apertures 12 provide for ventilation of the air space formed by the groove or gutter, thus to increase the rate of evaporation of moisture from the wall portion 30 as well as between this wall portion and the member 1.

While the member 1 has been shown in its relation to window aperture side frame members 2, it is, of course, to be understood that door aperture side frame members may be attached to the member 1 in the manner described with achievement of all of the above enumerated advantages through the groove or gutter means 9 of the member 1.

45 In the use of closure frame constructions of the type described above, it is impossible at all times to maintain a close, moistureproof, sealing engagement of the exterior vertical flange, such as 5, with the adjacent wall surfaces due to the diverse expansion and contraction of wall and frame members under extreme changes in temperature and/or humidity to which they are subjected by extreme changes in weather conditions.

55 The unpreventable entrance of rain, sleet and the like between the exterior flange of the top frame member and the adjacent wall surface of prior constructions was followed by collection thereof between the frame member and the adjacent wall surface.

60 Likewise, moisture in the wall gradually collected at the same location with resultant damage to the metallic frame member by reason of rusting and, in extreme cases, by escape of the moisture or water to the interior side of the frame member and into the enclosure.

65 As most clearly appears, from the above description, all of these disadvantages are totally obviated while the structural strength and rigidity

of the top frame member is, at the same time, materially enhanced by reason of the crenelated nature of the groove 9.

It will be seen that the provision of the groove or gutter means 9 with its draining and ventilating apertures 12 in addition to increasing the rigidity and strength of the member 1 also provides for condensation of moisture between the member 1 and the adjacent wall portion 4, while at the same time increasing evaporation of moisture from the wall portion 4 and collection of all moisture between the members 1 and 4 and the direction thereof through the drain apertures 12 to the atmosphere.

It is, of course, to be understood that the above 15 described structure is merely illustrative and in nowise limiting and that I desire to comprehend all modifications included within the scope of the appended claims and the invention.

Having thus fully described my invention, what 20 I claim as new and desire to secure by Letters Patent is:

1. In a closure frame member attachable to the top of a wall aperture, a vertical flange portion engageable with a vertical wall surface, a horizontal flange portion extending from said first flange portion and engageable with a horizontal apertured surface, and moisture collecting means integral with said horizontal flange portion comprising a downwardly offset apertured channel 30 formed integrally in said flange portion and providing moisture collecting and draining means while increasing the strength of said closure frame member.

2. As an article of manufacture for use as a 35 closure flange top section, a structural member having a vertical wall engaging flange portion, a horizontal flange portion, and offset apertured groove means formed in said horizontal flanged portion adjacent the vertical wall engaging flange 40

3. As an article of manufacture for use as a closure frame top section, a structural member having vertical wall engaging flange means, horizontal wall engaging flange means extending from said vertical wall engaging and integral 45 therewith, and apertured groove means in said last named flange means forming an air space between said flange means and an engaged wall surface for moisture collection and drainage and ventilation of wall portions adjacent the surfaces 50 engaged by said vertical and horizontal flange means.

4. As an article of manufacture for use as a closure frame top section, a structural member having vertical wall engaging flange means, horizontal wall engaging flange means extending from said vertical wall engaging flange means and integral therewith, and apertured groove means in said last named flange means forming an air space between said flange means and an engaged wall surface for moisture collection and drainage and ventilation of wall portions adjacent the surfaces engaged by said vertical and horizontal flange means, said apertured groove means imparting added rigidity to said horizontal wall engaging flange means.

EDWARD R. GUNTER.
